DESIGN FOR A BADGE OR SIMILAR ARTICLE

Ruth D. Gouldner, Los Angeles, Calif.

Application August 19, 1941, Serial No. 102,948

Term of patent 3½ years

To all whom it may concern:

Be it known that I, Ruth D. Gouldner, a citizen of the United States, residing at Los Angeles, in the county of Los Angeles and State of California, have invented a new, original, and ornamental Design for a Badge or Similar Article, of which the following is a specification, reference being had to the accompanying drawing, forming part thereof.

Fig. 1 is an enlarged face view of a badge or similar article embodying my new design.

Fig. 2 is a rear view of the same.

Fig. 3 is a side elevation of the same.

I claim:

The ornamental design for a badge or similar article, substantially as shown.

RUTH D. GOULDNER.
